[57] CLAIM

The ornamental design for universal safety blocks for dump trucks, as shown and described.

DESCRIPTION

FIG. 1 is a side elevational view of universal safety blocks for dump trucks showing our new design.

FIG. 2 is an elevational view of the opposite side thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is a side elevational view thereof partially in section taken along the line 7—7 of FIG. 3; and,

FIG. 8 is a side elevational view thereof partially in section taken along the line 8—8 of FIG. 3.

The transverse rod has been broken away in the middle in FIGS. 3, 4, 5, and 6 to indicate indeterminate length.
